(57) **CLAIM**

The ornamental design for a combined bag and strap, as shown and described.

DESCRIPTION

FIG. 1 is a perspective view of the combined bag and strap;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a schematic diagram, showing the combined bag and strap in a condition of use as being carried by a user; and,
FIG. 9 is a schematic diagram, showing the combined bag and strap in a condition of use as attached to a backpack. The broken lines depict portions of the combined bag and strap and environment of use that form no part of the claimed design.
